UNITED STATES PATENT OFFICE.

THOMAS J. MUMFORD, 2d, OF PLAINFIELD, NEW JERSEY.

COMBINED SQUEEZE AND JOLT RAMMING MACHINE.

1,242,364.

Specification of Letters Patent.

Patented Oct. 9, 1917.

Application filed February 25, 1916. Serial No. 80,368.

To all whom it may concern:

Be it known that I, THOMAS J. MUMFORD, 2d, a citizen of the United States, residing at Plainfield, in the county of Union and 5 State of New Jersey, have invented certain new and useful Improvements in Combined Squeeze and Jolt Ramming Machines, of which the following is a specification.

This invention relates to improvements 10 in squeeze and jolt ramming molding machines, that is to say, machines which are capable of being used to carry on a squeezing operation and also a jolt ramming operation. The invention has particular reference to that type of molding machine 15 known as a high trunnion squeezer although it is applicable to other forms of power operated molding machines.

It is one of the primary objects of my 20 invention to provide an improved molding machine of the character specified which is simple and economical in construction and efficient in operation and in which the parts are so arranged as to occupy a minimum 25 amount of space. Another and more specific object of my invention is the provision of an improved form of jolt attachment by means of which standard types of high trunnion squeezers or similar forms of 30 power squeeze molding machines now in use may be readily transformed into a combined squeeze and jolt ramming machine, and this substantially without the necessity 35 of replacing any of the standard parts of such machines, and at a minimum expense.

While, as pointed out, complete machines embodying my invention may be constructed *de novo*, I will show and describe my invention as it is used in transforming stand- 40 ard forms of power squeeze machines into a combined jolt and squeeze machine.

The foregoing, together with such other objects as may hereinafter appear, or are incident to my invention I attain by means 45 of a construction which I have shown in preferred form in the accompanying drawings wherein—

Figure 1 is a side elevation, partly in section, of a standard form of high trunnion squeezer to which my invention is to be applied; Fig. 2 is a similar view, but with my improvements embodied therein; Fig. 50 3 is an enlarged sectional view of a portion of the apparatus shown in Fig. 2; and Fig. 55 4 is a sectional detail taken on the line IV-IV of Fig. 3.

Referring first to Fig. 1, it will be seen that the machine comprises a base 7 which is preferably composed of two legs formed to support a cylinder member 8 and the 60 squeezing plunger 9 upon which are carried the mold parts to be operated upon. Mounted on the top of the base and to the rear thereof is an upstanding post 10, to the upper portion of which is pivoted a ramming yoke 11 in which the ramming block 12 is adjustably mounted by means of the threaded stem 13. At the front the yoke is provided with a strain link 14 which when in operative position is hooked over a projection or lug 15 formed on the cylinder 8, which link takes the strain of the squeezing. In order that the yoke may be readily manipulated before and after a squeezing operation, the spring 16 is provided, such 70 spring engaging the post casting 10 at one end and the yoke 11 at the other end. Fluid pressure is admitted into the bottom of the cylinder 8 to operate the plunger 9 in the usual manner. In the type of machine 80 shown, the cup leather 17 is used in place of the standard piston ring.

In transforming this machine into a combined squeeze and jolt ramming machine, the operation is as follows: The plunger 9 is removed and is tapped, as at 18, to receive the threaded portion 19 of a jolt operating piston 20 which will be further described. The plunger is also drilled at a plurality 90 of points to provide surge ports 21, (see Figs. 2 and 3). The cylinder 8 is also re- 95 moved from the machine and the end face thereof is machined for the attachment of the jolting cylinder 22. A central opening 23 is also drilled in the bottom of the cylinder, such opening having a diameter greater than that of the jolt plunger 20 and it is tapped, as indicated at 24, to receive the studs 25 which serve to retain the jolting cylinder 22 in position. The cylinder 22 is provided with an inlet port 26 and with an exhaust port 27, the inlet port being preferably controlled by a valve 28, said valve being normally in open position un- 105 covering the inlet port, and being closed by pressure accumulating under the lower and larger face thereof, 29, pressure being conducted thereto from the inlet 26 by means of the duct 30. The stem 31 of the valve projects into the cylinder 22 in position to be engaged by the jolt plunger 20 as the latter moves downwardly. Intermediate its

100

110

end the plunger 20 is provided with a reduced portion 32 which provides an annular space 33 communicating with the upper end of the inlet port 26. Air pressure finds its way into the cylinder 22 beneath the plunger 20 by means of the openings 34 and 35 which may be drilled or otherwise formed in the plunger 20. In order that the parts may be readily assembled and the ports conveniently drilled, the cylinder 22 is provided with a separable bottom portion 36 by means of which arrangement the valve parts are made readily accessible.

A combined impact and valve member A is inserted between the main cylinder 8 and the plunger 9, such member comprising a leather ring or pad 37 which is retained in normal position by means of a stiffening member 38, preferably sheet steel. Air is introduced for a squeezing operation into the cylinder 8 beneath the impact and valve member A through the port opening 39.

When the machine is operated as a squeezer, assuming that the mold parts have been placed in position on the plunger 9, and that the yoke has been brought into operative position and locked, air is introduced into the cylinder 8 beneath the member A through the port 39 and the plunger 9 is thereby elevated and squeezes the mold, during such operation the member A acting as a valve to close the surge ports 21 formed in the bottom of the plunger 9. When, however, the machine is utilized for a jolt ramming operation, air is introduced into the cylinder 22 through the inlet port 26 and port openings 34 and 35, thereby elevating the jolting plunger 20 which carries with it the plunger 9. When the plunger has been raised a distance sufficient to cause the annular chamber 33 to communicate with the exhaust port 27, there will follow, because of the exhaust of pressure, a reduction of pressure in the space above the valve 28 which, in conjunction with the pressure which accumulates beneath the lower face of the valve, will cause the valve to move upwardly to closed position, covering the inlet port 26. Upon exhaust of pressure within the cylinder through the exhaust port 27 the plunger and its associated parts will fall, the impact being received by the member A. As the cylinder falls, it engages the stem 31 of the valve and moves it to open position when the operation will be repeated until such time as the mold has been jolt rammed and the operator turns off the valve controlling the supply of pressure to the inlet port 26. During this jolt ramming operation the surge ports 21 provide means for the ready flow of the air confined in the cylinder 8, thereby preventing the formation of a vacuum and causing the machine to operate easily. To facilitate this operation, a port 40 is drilled in the wall

of the plunger 9 in such position as to be uncovered when the plunger 9 reaches its upper stroke limit during jolting.

It will be seen from the foregoing that my invention is simple in character, occupies a minimum amount of space and is so constructed that it may be readily applied to standard forms of power squeezers to transform them into jolt and squeeze machines.

It will be noted that the machine as thus transformed is economical in operation because of the fact that a jolting piston of relatively small area is used. For a squeezing operation, a plunger having a large effective area is required in order to secure the pressure requisite to properly squeeze the mold. Such a large area, however, is unnecessary for jolting purposes and if used, would waste considerable pressure. With a jolt plunger of small dimension, this wastage is avoided.

I claim:

1. A change-over jolt attachment for a squeezer molding machine comprising a member adapted to coöperate with the squeezer cylinder, a plunger working in said member coöperating with the squeezer plunger, and means for supplying air for operating said change-over plunger for a jolt ramming operation.

2. A change-over jolt attachment for a squeezer molding machine comprising a member adapted to be secured to the squeezer cylinder, a plunger coöoperating with the squeezer plunger, and means for supplying air for operating said change-over plunger for a jolt ramming operation.

3. A change-over jolt attachment for a squeezer molding machine comprising a member adapted to be secured to the squeezer cylinder, a plunger coöperating with the squeezer plunger, and a valve controlling the air supply for said change-over plunger to secure a jolting operation.

4. A change-over jolt attachment for a squeezer molding machine comprising a member adapted to coöperate with the squeezer cylinder and provided with a plunger coöperating with the squeezer plunger and means for supplying air for a jolting operation.

5. A change-over jolt attachment for a squeezer molding machine comprising a member adapted to coöperate with the squeezer cylinder and provided with a plunger coöperating with the squeezer plunger and means for breaking vacuum in the squeezer cylinder when the machine is operating as a jolt ramming machine.

6. A change-over jolt attachment for a squeezer molding machine comprising a cylinder adapted to be secured to the bottom of the squeezer cylinder, a plunger working therein adapted to be secured to the squeezer

plunger, and means for supplying air for a jolting operation.

7. A change-over jolt attachment for a squeezer molding machine comprising a cylinder adapted to be secured to the bottom of the squeezer cylinder, a plunger working therein adapted to be secured to the squeezer plunger, and an automatic valve for controlling the air supply for said jolt cylinder for a jolting operation.

8. A combined jolt and squeeze ramming molding machine comprising a squeezer cylinder having an opening in the bottom, a squeezer plunger working in said cylinder, a smaller jolt cylinder depending below the squeezer cylinder, a jolt plunger in said jolt cylinder adapted to pass through said opening in the squeezer cylinder and coöperate with the squeezer plunger, means for introducing fluid pressure under the squeezer plunger for the squeezing operation, and means for introducing fluid pressure under the jolt plunger for the jolting operation.

9. A combined jolt and squeeze ramming molding machine comprising a squeezer cylinder having an opening in the bottom, a squeezer plunger working in said cylinder, a smaller jolt cylinder depending below the squeezer cylinder, a jolt plunger movable

with the squeezer plunger and projecting through the opening in the bottom of the squeezer cylinder and working in said jolt cylinder, means for introducing fluid pressure under the squeezer plunger for the squeezing operation, and means for introducing fluid pressure under the jolt plunger for the jolting operation.

10. A combined jolt and squeeze ramming molding machine comprising a squeezer cylinder having an opening in the bottom, a squeezer plunger working in said cylinder, a smaller jolt cylinder depending below the squeezer cylinder, a jolt plunger movable with the squeezer plunger and projecting through the opening in the bottom of the squeezer cylinder and working in said jolt cylinder, means for introducing fluid pressure under the squeezer plunger for the squeezing operation, and means for introducing fluid pressure under the jolt plunger for the jolting operation, and valve mechanism in the jolt cylinder in position to be engaged by the jolt plunger for controlling the jolting operation.

In testimony whereof I have hereunto signed my name.

THOMAS J. MUMFORD 2ND.
